UNITED STATES PATENT OFFICE

2,439,990

PATTERN CONTROL MEANS FOR
KNITTING MACHINES

Tom Read Ryan, Trenton, Ga.

Application December 8, 1943, Serial No. 513,407

4 Claims. (Cl. 66—155)

1

My invention relates to improvements in full-fashioned hosiery knitting machines, more particularly of the "Reading," single-unit type of commerce.

Among the important objects of my invention is to equip such machines with improved auxiliary mechanism for predetermining knitting of different sizes of hosiery without changing the previous set-up of the usual control buttons on the pattern chain for controlling narrowing and other operations, and which may be embodied in present day machines of the type above indicated without necessitating extensive alteration in the basic structure of such machines.

Another object is to provide an attachment for automatically predetermining the number of courses for different sizes of hosiery, the attachment being adapted for presetting to select the courses to be run and the size to be produced.

Other and subordinate objects are also comprehended by my invention, all of which, together with the precise nature of my improvements, will be readily understood when the succeeding description and claims are read with reference to the drawings accompanying and forming part of this specification.

In the drawings:

Figure 1 is a fragmentary view in front elevation of a portion of a full-fashioned hosiery knitting machine of the type above designated equipped according to my invention,

Figure 2 is a view in top plan,

Figure 3 is a view in top plan of the dog carrier, parts carried thereby and the counter and narrowing control rods drawn to an enlarged scale,

Figure 4 is a view in rear elevation of the same,

Figure 5 is a view in front elevation of said carrier, rods, and parts on the carrier,

Figure 6 is a view in front end elevation of the same,

Figure 7 is a view in longitudinal section taken on the line 7—7 of Figure 6,

Figure 8 is a view in transverse section taken on the line 8—8 of Figure 5,

Figure 9 is a view in side elevation of the size selector dial wheel and the size selector shaft.

Figure 10 is a view in end elevation of the same,

Figure 11 is a fragmentary view in plan of the pattern chain, parts of the chain drive, and drive disabling means, the shogging truck, the truck locking yoke, and parts associated therewith,

Figure 12 is a detail view in front elevation with parts shown in section of the chain driving ratchet wheel, pawl, and the tappet arm on the narrowing control rod,

2

Figure 13 is a view in perspective of the driving pawl for the ratchet wheel of the chain drive,

Figure 14 is a fragmentary view in plan of the pattern chain,

Figure 15 is a view in transverse section taken on the line 15—15 of Figure 14 and showing one of the control buttons, and

Figure 16 is a similar view of a modified form of control button.

10 Figure 17 is a detail view of the operating pawl for the course counter and the detent means therefor.

Referring to the drawings by numerals, the type of knitting machine, hereinbefore designated, and 15 with which my invention is more particularly concerned, has been shown in part only as sufficient to a proper understanding of my invention.

Referring now to Figures 1, 2 and 11, more particularly, such machines comprise a front beam 1 supported by frame uprights 2 forming part of superstructures supporting various elements of the machines, such as the control shaft 3 and hand wheel 4, also the control rod 5 which need merely to be identified in passing. In the rear 20 of the beam 1 is an elevated, constantly driven cam shaft 6 which is endwise movable to control various operations of the machine not necessary to enter into herein, with the following exceptions:

The cam shaft 6 has fast thereon a pair of side-by-side, laterally spaced cams 7, 8 for effecting endwise shifting of said shaft in opposite directions, respectively. Such shifting of the cam shaft from normal position, to the right as viewed in Figures 1, 2 and 11, shifts knitting cams 35 mounted on the shaft, as at 9, out of action and brings into action narrowing, or picoting, cams mounted on said shaft, as at 9', whereas, movement of the cam shaft 6 to the left back to normal position shifts said narrowing cams 9' out of 40 action and the knitting cams 9 back into action.

The cams 7, 8, and hence the cam shaft 6, are shifted under control, primarily, of a chain motion comprising a pattern chain 10 mounted on an intermittently driven sprocket wheel 11, the chain 45 having affixed thereto a longitudinal row of spaced-apart narrowing buttons 12 which, as the chain travels clockwise, as viewed in Figures 1, 2 and 11, successively raise a forked yoke 13, pivoted, as at 14, on a fixed bracket 15. Raising of the 50 yoke 13 removes an upper tine 16 thereof from behind a shoulder 17 on the spindle 18 of a shogging truck, which, when thus released, is moved rearwardly by a suitably connected spring 19 to move a roller 20 on said spindle 18 into cooperative relation to the cam 7 such that under rota-

tion of the cam shaft 6 said shaft is shifted to the right. As the cam shaft 6 and cams 7, 8 complete one revolution, a supplemental cam 21 on the cam 7 engages a roller 22 carried by an arm 23 fast on the spindle 18 and retracts said spindle 18 and roller 20 to position said roller into cooperative relation to the cam 8 such that said shaft 6 is shifted to the left back to normal position. When the spindle 18 is retracted, the yoke 13 drops, under the influence of gravity, and replaces the tire 16 behind the shoulder 17 to lock the spindle of the shogging truck, and hence said truck, in ineffective position. The lower tire 24 of said yoke 13, when the latter is raised, engages a shoulder 25 on the spindle 18 and limits rearward movement of the shogging truck. As illustrated, a suitable lifting arm 26 vertically swingable on the pivot 14 of the yoke 13 and extending under said yoke and over the buttons 12 is raised by said buttons to raise said yoke and is provided with a suitable yielding lateral extension, such as a spring 28, between the same and said yoke 13 so that said arm may be raised idly by said buttons when the yoke 13 is locked down, as occurs in operations presently explained.

The sprocket wheel 11 is rotated step by step through the medium of a constantly driven ratchet wheel 29 and a pawl carrier lever 30 oscillating vertically about the shaft 31 of said wheel 11 and provided with a driving pawl 32 pivoted, as at 33, thereon to ratchet over said ratchet wheel. A rocker 34 journalled on a fixed shaft 35 operates said lever 30 in a driving direction in opposition to a suitably arranged spring, not shown. A supplemental cam 36 on the cam 8, at the end of each cycle of rotation of the cam shaft 6, engages a roller 37 on said rocker 34 and operates the rocker to advance the ratchet wheel 11 and chain 10 one step.

The parts of the machine described are well known in the art and need not be entered into in further detail herein. For a more complete disclosure of such machines reference may be had to U. S. Patents Nos. 2,033,301, 2,214,363, and 2,295,782.

According to my invention, at the left of the chain 10 is a course control and counter 38 of the usual well known construction with the exceptions presently noted. Such instrumentalities in these machines control, in a manner well understood in the art, the number of courses to be knit and embody a drive comprising a ratchet wheel driven by a constantly operating pawl 39 adapted to be swung, as on a pivot 40, into an ineffective position to disable the counter. In accordance with my invention, the counter 38 is provided with three ratchet wheels 41, 42, 43 having 19, 25 and 31 teeth, respectively, and the driving pawl 39 is adapted for setting to operate the counter through any one of said wheels for a purpose presently seen. A disc 44 on the counter 38 is provided with an edge notch 45, the disc rotating once for each complete cycle of operation of the counter and serving a purpose to be explained.

In the drive for the course control counter 38, according to my invention, the pivot 40 of the operating pawl 39 mounts the pawl on one end of a bell crank pawl carrier 96 suitably mounted to rock about the common axis of said wheels 41, 42, 43. A coil spring 96 attached in any suitable manner to the other end of said pawl carrier 96 and to the beam 1 urges said carrier clockwise, as viewed in Figure 1. A rocker 98 pivoted intermediate its ends, as at 98, on a fixed part 99, with one end underlying said other end of

the carrier 96, and a roller 99 on its other end, operates said carrier counter-clockwise, as viewed in Figure 1, to impart movement to said pawl 40 for operating a selected one of said ratchet wheels 41, 42, 43. A cam 100 on the cam shaft 60 engages the roller 99 to rock said rocker 98 in the proper direction for operation of said carrier. The pivot 40 of said pawl 39 has the form of a rod extending laterally from said carrier 96 over the ratchet wheels 41, 42, 43, and along which said pawl 39 is manually slideable to set the same into operative relation to either of said wheels. A suitable spring-pressed detent bolt 101 is slidably mounted in a bushing 102 in said pawl 39 for engagement with notches 103 in said pivot bar to releasably retain the pawl 39 in set position. A spring 105 suitably connected to said pawl 39 and to a relatively fixed part acts to engage the pawl with the selected ratchet wheel 41, 42, 43.

20 Intermediate the chain 10 and the course control and counter 38 is a rectangular, box-like dog carrier 46 open at its top and ends and having a depending bottom guide flange 47 by means of which it is slidably mounted for endwise reciprocation in the line of the chain 10 upon horizontal intermediate control rods 48, 49, respectively, extending along the front of the machine.

The rods 48, 49 are slidably extended, for endwise movement, through a guide bar 50 extending horizontally outwardly from the front beam 1. The front counter control rod 48 is connected at what constitutes its left end, in any suitable manner, for instance as represented, to the pawl 40 to normally hold the same in ineffective position, and so that under leftward endwise movement of said rod, said pawl will be released to operate said counter through a selected ratchet wheel 41, 42 or 43, selected in the manner already described. As shown, the connection takes

40 the form of a bar 104 extending laterally from said rod 48 in front of and across the pawl 39 above the pivot 40 thereof. The rear, narrowing control rod 49 is pivotally connected at its right end to the lower end of a vertical lever 51 pivoted 45 intermediate its ends, as at 52, on a fixed bracket arm 53, with its upper end slideable on a push rod 54 against a stop collar 55 on one end of said rod. The other end of the push rod 54 is pivotally connected to the yoke 13, as at 56, the arrangement being such that if the narrowing control rod 49 is moved to the left, the lever 51 will be swung against the stop collar 55 to hold the yoke 13 down so that it cannot be raised to release the spindle 18 of the shogging truck. The 55 rods 48, 49 are provided to the left of the dog carrier 46 with abutment plates 56, 57, respectively, fast thereon the purpose of which will be presently seen.

Pivotally mounted intermediate their ends in 60 the dog carrier 46, to rock vertically on a cross shaft 58, are two front and rear series 59, 60 of bar-like, side-by-side dogs extending horizontally out of the left end of said carrier and overbalanced on said shaft so that they tend to rock 65 under the influence of gravity to lower their left ends, those of the front series 59 into abutting relation to the plate 56 of the counter control rod 48, and those of the series 60 into similar relation to the plate 57 of the narrowing control rod 49. A size selector shaft 61 journalled in the sides 70 of the carrier 46 extends across the tail ends of said series 59, 60 of dogs on the right side of the shaft 58 and is equipped on one end thereof with a hand-operated selector dial wheel 62 marked on 75 its face to indicate, in the present instance, five

sizes of hosiery, to wit, sizes 8½, 9, 9½, 10 and 10½. The shaft 61 is formed with longitudinally spaced notches 63 spaced around the same in different angular relation so that when the wheel 62 is turned and set to select a size with the selected size marking uppermost, certain of the notches 63 will be disposed directly over certain of the dogs of the series 59, 60 and said dogs thereby selected for release to rock into effective positions into the described abutting relation to the plates 56, 57.

A transverse, dog-control shaft 64, journaled in the sides of the carrier 46, underlies the series of dogs 59, 60 to the left of the shaft 58 and is provided with a series of longitudinally spaced notches 65, similar to notches 63. The shaft 64 is designed for rotation, step by step, to position certain notches 65 at each step of rotation under the series 59, 60 of dogs and thereby permit the same to drop into effective positions. A pair of detent dogs 66, 67 pivoted on the shaft 58 and engaging notched wheels 68, 69 on the shafts 61, 64, respectively, prevent over-rotation of said shafts.

The dog-control shaft 64 is rotated step by step, counterclockwise, as viewed in Figures 1 and 5, under reciprocation of the dog carrier 46 by means of a ratchet wheel 70 fast on one end thereof, an upstanding rock arm 71 swingable on said end of said shaft, a ratchet pawl 72 pivoted, as at 73, on said arm, and a push rod 74 pivotally connected to the upper end of said arm and extending forwardly of the carrier 46 with its other end pivotally connected to an upstanding post 75 on the beam 1.

For reciprocating the dog carrier 46, a pendant lever 76 pivoted at its upper end on the pivot shaft 14, in the line of the chain 10, is utilized, and which is provided with a cam lug 77 facing said chain 10, and a push rod connection 78 to the carrier 46. A longitudinal row of spaced-apart control buttons 79, similar to the narrowing buttons 12, are provided on said chain 10 to successively engage said cam lug 77 and swing the carrier-operating lever 76, clockwise as viewed in Figure 1, in opposition to a suitably connected lever tensioning spring 80, whereby said carrier 46 is moved forwardly to be returned by said spring when the active button 79 wipes past said lug 77.

Returning now to the course control and counter 38, in the full cycle position thereof, a bell crank dog 81 pivoted, as at 82, on a fixed post 83, has one end adapted to seat in the notch 45 of the disc 44 so that as soon as said counter begins to operate, said end of said dog is cammed out of said notch and the dog swung clockwise, as viewed in Figure 1. A push rod 84 suitably connected at one end to the other end of said dog 81 has its other end slidably mounted in the guide post 82' and provided with a tappet arm 83' opposed to the tail end of the ratchet-driving pawl 32, so that when the bell crank dog 81 is swung as described, the tappet arm 83' swings said driving pawl out of driving relation to the ratchet wheel 29 and thereby disables the drive to the chain 10. When the notch 45 again registers with the said dog 81, the latter drops into the notch 45 under the urge of a suitable spring 85 on said rod 84, and the driving pawl 32 is released for effective operation of the chain drive.

There is a group of three control buttons 79 on the chain 10 spaced close together to function as one button and nine control buttons 79 following the group, ten ratchet teeth on the ratchet wheel

70, and five dogs in each series 59, 60. If desired, the modified elongated button shown in Figure 16 may be used in lieu of the said group of three. The dogs in the series 59 are designated 86, 87, 88, 89, 90, and those of the series 60 are designated 91, 92, 93, 94, 95. The first buttons, to wit, said group, as shown at the right in Figure 14, are placed in advance of the main leg-narrowing button 12 of the chain 10, the fourth, fifth, sixth, seventh and eighth control buttons 79 are placed on the chain alongside the second, third, fourth, fifth and sixth heel-narrowing buttons 12, and the ninth, tenth, eleventh and twelfth control buttons 79 are placed on the chain just after the heel-narrowing buttons 12, or in short, in the sole.

In the operation of the described invention, the selector shaft 61 is first set to select the size of hosiery to be run, in the manner already described. As soon as a control button 79, or the group above mentioned, engages the cam lug 77 of the lever 76, said lever is operated to move the dog carrier 46 to the left. In the setting of the selector shaft 61, certain dogs of either or both series are released and drop into effective positions so that under such forward shifting of the dog carrier 46, the plates 56, 57 are engaged by the effective dogs of the series 59, 60 and both rods 48, 49 move to the left. Leftward movement of the counter control rod 48 renders the course and control counter 38 operative in the manner described to make a complete revolution. Initial operation of the course control and counter 38 disables the driving pawl 32, as we have already seen, and stops the chain drive with one, or the group, of buttons 79 engaged with the cam lug 77, thus holding the dog carrier 46 forward. As of course will be understood, the group of dogs 79 engages the cam lug 77 successively as well as the other buttons 79. This stops the chain 10 while course knitting is proceeding. Leftward movement of the narrowing control rod 49 blocks, or prevents, raising of the yoke 39 by the narrowing buttons 12, as already described. During leftward movement of the dog carrier 46, the rocker arm 71 is moved clockwise, as viewed in Figures 1 and 5, to set the pawl 73 for operation of the ratchet wheel 70 and the dog control shaft 64 one step under return shifting, or movement, of said dog carrier. As soon as the disc 44 of the course control and counter 38 completes a revolution, the driving ratchet 32 is released, in the manner previously described, the chain 10 is again driven, the group of buttons 79, or a button, wiping past the cam lug 77 and releasing the lever 76 for return by the spring 80, whereby the dog carrier 46 is returned rightwardly to starting position. The plates 56, 57 are thus released, also the rods 48, 49, so that the yoke 13 is released in a manner which will now be clear, whereby narrowing is permitted under the control of the narrowing buttons 12 and the drive to the course control and counter 38 is rendered ineffective, also as previously described. Under return movement of the dog carrier 46, the rocker arm 71 is swung counterclockwise, as viewed in Figure 1, to operate the ratchet wheel 70 and dog control shaft 64 one step of movement under which other dogs, or a dog, of the series 59, 60, as the case may be, are permitted to drop to effective position for operation against the plates 56, 57 under subsequent leftward movement of the dog carrier 46. There being ten control buttons 79, counting the group as one, the operations described are repeated ten times during the knitting of each piece of hosiery. When the dial

wheel 62 is set for 8½ size hosiery, dog 91 is effective, for size 9, dogs 87, 92, for size 9½, dogs 86, 87, 88, 93, for size 10, dogs 86, 87, 88, 89, 94, for size 10½, dogs 86, 87, 88, 89 and 90 and 95.

As will now be seen, the size of the hosiery knitted depends upon varying the operations of the machine as regards narrowing, by preventing narrowing a different number of times for different sizes of hosiery. As previously stated, there are ten buttons 79 on the chain 40 and all ten are active in each cycle of operation of the machine in knitting each size of hosiery. The number of dogs in series 59, 60 which are effective in each cycle of operation of the machine determine the number of times in the cycle of operation that narrowing is prevented. Setting of the selector shaft 61 predetermines the number of dogs in the series 59, 60 to be effective in accordance with the number of times narrowing is to be prevented for hosiery of different sizes. The dogs in series 59, 60 thus pre-selected have a definite time to work in the cycle of operation of the machine and the time of operation is controlled by rotation of the dog control shaft 64.

By shifting the pawl 39 for operation of the course control, and counter 38 through the medium of different ratchet wheels 41, 42, 43, the machine may be conditioned for knitting different numbers of courses during each complete rotation of disk 44 after courses.

As may be further explained, the two series of dogs 59, 60 control operation of the course control counter 38 in producing two-leg sizes with five different foot sizes, and the dogs of each series are effective, one at a time, at different times, in controlling said counter for varying the number of courses run in the two different sizes independently of the narrowing operations for which the buttons 12 are set on the chain 40. Of course, during operations accomplished under control of the buttons 79, the spindle 18 of the shogging truck is locked against operation so as to prevent other operations of the machine not incident to the operations accomplished under control of the buttons 79. The buttons 79 are arranged relative to the narrowing buttons 12 to control course running in timed relation to different narrowing operations, and, of course, the positions of the buttons 79 may be varied with relation to the narrowing buttons 12, as occasion may require.

Setting of the selector dial wheel 62 predetermines the size of the stocking to be knit by selecting dogs in series 59, 60 that are to be rendered effective in knitting the selected size of stocking. The ratchet wheel 70 determines when the selected dogs 59, 60 shall be rendered effective and makes a complete revolution in order to permit each dog in the series 59, 60 to become effective if selected, and to render nonselected dogs ineffective. For instance, when the selector dial wheel 62 is set for size 8½, one dog 91, in series 59, is selected and rendered effective by revolution of the ratchet wheel 70, and nine dogs, in series 59, are not selected, nor rendered effective. In knitting size 9, two dogs 87, 92 are selected and rendered effective, and eight dogs are not selected nor rendered effective, and so on. The dogs in each group 59 add the length or courses to the stocking, each dog in this group rendering the course control counter 38 operative for a complete revolution. Thus, one cycle, or one revolution, of the course control counter 38 determines the difference between sizes. If the operating pawl 39 is set for operating the course counter control 38 by the ratchet wheel 41, eighteen

courses will be run in the predetermined size of stocking. If said pawl 39 is set for operation of the course control counter 38 through ratchet wheel 42, twenty-four courses will be run in the predetermined size or selected size of stocking, and if said pawl 39 is set for operation of the course control counter 38 through ratchet wheel 43, thirty courses will be run in the predetermined or selected size of stocking. Thus, the operation effected by ratchet wheels 41, 42, 43 does not vary when changing to different sizes of stockings. The only change effected is in style and in varying the number of courses in a predetermined size.

The dogs in the series 60 are selected and rendered effective through setting of the dial wheel 62 and during each revolution of the ratchet wheel 70 for any size stocking by causing the machine to omit narrowing when any one of these dogs becomes effective, as previously described. Only one dog of series 60 is rendered operative at a time in any predetermined or selected size, and each is rendered operative for a different size of stocking.

The buttons 79 are arranged on the chain as desired. The buttons 79 spaced apart to act singly cause the course control counter 38 to make a single revolution. By placing the buttons 79 close together, the same act as one to cause the course control counter 38 to operate multiple revolutions and the machine to run multiple or successive courses, the number of which is determined by the number of buttons 89 placed close together. When the buttons 79 are placed opposite buttons 12 on the same chain link, the buttons 79 act on lug 71 several chain racks in advance of the buttons 12 because buttons 79 act at the left side of the sprocket 11 just below the axis of rotation thereof, whereas, buttons 12 act at the top of said sprocket about ninety degrees in advance of buttons 79.

As will be understood, in the type of machine with which this invention is particularly concerned, the size of the hosiery is marked or indicated thereon, as an incident to narrowing operations along the sole of the hosiery and by small nubs formed along the seam of the sole. This is conventional, and it is therefore not deemed necessary to illustrate the same. However, as will also be clear, since in my invention the sizes of hosiery to be run are predetermined, and the narrowing operations for each size, the size marking is likewise predetermined by setting of the selector dial wheel 62 to predetermine the size to be run.

Also, it will be understood then by adding dogs such as 88, 89, the knitting of other sizes than those mentioned may be predetermined and leg sizes may be predetermined by using dogs 81, 88, 89, 90 in leg knitting as well as in foot knitting.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In a knitting machine, the combination with a main cam shaft endwise movable in opposite directions into knitting and narrowing positions, respectively, a pattern chain, a chain drive, means to move said shaft under control of said chain, and course control means normally ineffective, of means to render said course control means ef-

fective comprising an endwise movable rod, a reciprocating dog carrier, means operative by said chain to move said carrier in one direction, an abutment on said rod, and a dog on said carrier for engaging said abutment.

2. In a knitting machine, the combination with a main cam shaft endwise movable in opposite directions into knitting and narrowing positions, respectively, a pattern chain, a chain drive, means to move said shaft under control of said chain, and course control means normally ineffective, of means to render said course control means effective comprising an endwise movable rod, a reciprocating dog carrier, means operative by said chain to move said carrier in one direction, an abutment on said rod, a dog on said carrier for engaging said abutment, and means operative by said course control means when effective to disable the chain drive.

3. In a hosiery knitting machine, the combination with a main cam shaft endwise movable in opposite directions into knitting and narrowing positions, respectively, a pattern chain, a chain drive, means to move said shaft under control of said chain, and a normally ineffective course control and counter, of means to simultaneously render said counter effective and disable said shaft moving means comprising a reciprocation dog carrier, a pair of rods endwise movable to render said counter effective and disable the shaft moving means, respectively, a pair of abutments on said rods, respectively, means operative by said chain for repeatedly moving the carrier in one direction, two series of dogs on said carrier for engaging said pair of abutments, respectively, in selected numbers under repeated movement of the carrier in said one direction, means to predetermine selection of the number of dogs in accordance with the size of hosiery to be knit, and means to complete selection of the dogs operative under repeated reciprocation of said carrier.

4. In a hosiery knitting machine, the combination with a main cam shaft endwise movable

in opposite directions into knitting and narrowing positions, respectively, a pattern chain, a chain drive, means to move said shaft under control of said chain, and a normally ineffective course control and counter, of means to simultaneously render said counter effective and disable said shaft moving means comprising a reciprocation dog carrier, a pair of rods endwise movable to render said counter effective and disable the shaft moving means, respectively, a pair of abutments on said rods, respectively, means operative by said chain for repeatedly moving the carrier in one direction, two series of dogs on said carrier for engaging said pair of abutments, respectively, in selected numbers under repeated movement of the carrier in said one direction, means to predetermine selection of the number of dogs in accordance with the size of hosiery to be knit, means to complete selection of the dogs operative under repeated reciprocation of said carrier, and means operative by said counter when rendered effective to disable said shaft moving means.
